METHOD OF REMOVING MERCAPTANS
FROM HYDROCARBON LIQUIDS

Lawrence M. Henderson, Winnetka, and George W. Ayers, Jr., Chicago, Ill., assignors to The Pure Oil Company, Chicago, Ill., a corporation of Ohio

No Drawing. Application September 5, 1941,
Serial No. 409,652

21 Claims. (Cl. 196—30)

This invention relates to a method of removing acidic bodies from otherwise neutral water immiscible fluids. More particularly, this invention is directed to the problem of removing mercaptans from hydrocarbon oils.

This application is a continuation in part of application, Serial No. 388,982, filed April 17, 1941, in the names of Lawrence M. Henderson and George W. Ayers, Jr.

Hydrocarbon oils, particularly light distillates resulting from cracking higher boiling fractions frequently contain mercaptans and other acidic sulfur compounds which require removal in order to render the oil "sweet" and non-corrosive. It has been common practice in the petroleum refining art to remove part of the sulfur compounds by washing with caustic alkali and then to sweeten with doctor solution. The disadvantage involved in this type of treatment is that a considerable portion of the sulfur remains in the oil or distillate and adversely affects the anti-knock properties of the gasoline. Gasoline containing sulfur compounds such as organic disulfides, usually not only has a lower octane rating than substantially sulfur-free gasoline, but requires much more tetra-ethyl lead to raise its octane rating to a given value.

More recently an improvement in caustic washing for removal of mercaptans and other sulfur compounds has been effected by adding to the caustic solution materials such as sodium or potassium isobutyrate, commonly known as "solutizers" or solubility promoters, i. e., substances which enable the alkali solution to extract larger amounts of acidic substances such as mercaptans from fluids in which they are contained.

We have discovered that the results obtained by washing with caustic alkali solution either alone or containing known solubility promoters can be considerably improved upon by adding to caustic alkali solution poly-hydroxy-diphenyls which are of themselves good solubility promoters and which have the further ability to act as solvrentizers for solubility promoters whose solubility in alkali solutions is low. By the term "solvrentizer" is meant a substance which will enable larger quantities of the solubility promoter to dissolve in the caustic solution.

It has been found that soaps of alicyclic carboxylic acids such as naphthenic acids are good solubility promoters. However, caustic alkali solutions of fairly high concentration will dissolve only relatively small quantities of naphthenic or other alicyclic carboxylic acids and the soaps

thereof, and in the quantities that the soap or acid is dissolved in the caustic alkali, it has no material effect insofar as enhancing the ability of the caustic solution to remove acidic substances such as mercaptans and thiophenols from hydrocarbon oils. However, if a material is added having the ability to increase the solubility of the soap or acid in the caustic alkali and a sufficient amount of soap or acid is added to the caustic solution, the ability of the caustic to remove mercaptans and other sulfur compounds is greatly enhanced.

On the other hand, caustic alkali solutions of low concentrations will dissolve relatively large amounts of naphthenic or other acids and their soaps, but in low concentrations the caustic alkali solution per se or with addition of the acid or soap is relatively ineffective in removing mercaptans from the oil. If an attempt is made to increase the concentration of the caustic to a point where it is fairly effective in removing mercaptans, the naphthenic acid or other acid soap precipitates out of solution.

Although we have found that the poly-hydroxy-diphenyls in general are useful as solubility promoters and as solvrentizers, the dihydroxy-diphenyls, and particularly those in which the hydroxy groups are in ortho position to each other are particularly effective. As an example of a compound within the class we have set forth, is 3,4-dihydroxydiphenyl.

In order to realize to an appreciable extent the benefits of the invention, the solution should contain at least 5% by weight of free alkali metal hydroxide, preferably sodium or potassium hydroxide. By "free alkali metal hydroxide" it is meant hydroxide present in the solution in excess of the amount required to stoichiometrically react with the solvrentizers and solubility promoters present. Thus, irrespective of whether the solutizers or solubility promoters are added to alkali solutions in acidic form or as the alkali metal reaction products thereof, the finished treating solutions are considered to be alkali metal hydroxide solutions containing the alkali metal reaction products of the materials employed as solvrentizers and solubility promoters.

When used as solvrentizer, the amount of the polyhydroxy-diphenyl may vary with the particular solutizer used since some solubility promoters require less solvrentizer to effect solution thereof than do others. We have found that amounts as low as 2%, and amounts up to 40%, of the polyhydroxy-diphenyls may be used. It is preferred that in no case should the amount

of solventizer exceed about 90% of the maximum amount soluble in the solution. The ratio by weight of solventizer to solubility promoter is ordinarily about 1:1 to 1:3 for maximum solubility of the solubility promoter.

The acidic materials and/or the alkali metal reaction products thereof which have been found to be particularly effective as solubility promoters are the naphthenic acids and their metal salts, although it is to be understood that the polyhydroxy-diphenyls are also useful as solventizers in connection with other types of solubility promoters such as the low boiling fatty acids, i. e., fatty acids having less than 7 carbon atoms in the molecule, and their alkali metal salts. By the term "naphthenic acids" it is intended to include all alicyclic acids which occur naturally in crude petroleum and which are predominantly cyclic in structure such as carboxylic acids of cyclopentane and cyclohexane ring structure. These acids, generally speaking, fall within the empirical formulae $C_nH_{2n-1}COOH$, $C_nH_{2n-3}COOH$ and $C_nH_{2n-5}COOH$ and contain a cyclo-paraffinic ring having a carboxyl group attached to carbon in the ring or to an aliphatic chain which is in turn attached to carbon in the ring. The acids may be mono- or poly-cyclic, usually the former. An increase in the length of the aliphatic chain or in the number of aliphatic group substituents increases the tendency of the acids to behave as aliphatic acids. Since soaps of aliphatic acids, even those of as low molecular weight as heptylic acid, are too insoluble in sodium hydroxide solution to possess substantial merit as mercaptan solubility promoters, it is not desirable to have too many aliphatic carbon atoms per molecule present because of the concomitant low solubility. It is accordingly preferred to use those naphthenic acids which have at least a definite minimum solubility in aqueous alkali solution. Acids which have this alkali solubility are those acids which dissolve substantially completely to the extent of 18.7 pounds in a solution of 6.3 pounds of commercial 5° cresol, 18.3 pounds of sodium hydroxide and 56.7 pounds of water at temperatures of about 70° F. It is apparent that in applying this solubility test to compositions containing mixtures of naphthenic acids of varying molecular weight and structure, that some of the acids may dissolve and others remain undissolved. If the dissolved acids are soluble to the aforementioned extent, they are alkali-soluble within the meaning of this invention. Naphthenic acids containing over about 8 or 9 carbon atoms per molecule, such as those containing between about 11 and 16 carbon atoms, are particularly effective. The naphthenic acids are especially useful if it is desirable to use sodium hydroxide solution which ordinarily is the cheapest of the available strong bases since the naphthenic acids have been found to have considerably greater solubility in sodium hydroxide solutions than aliphatic acids of a corresponding number of carbon atoms.

When using the polyhydroxydiphenyls alone as solubility promoters in connection with alkali metal hydroxide solutions, the polyhydroxydiphenyls should be present in solution in amounts not less than 10% by weight of the solution and may be used in amounts up to substantially the maximum solubility, although it is preferable not to use more than 90% of the maximum amount which is soluble in the solution. The free alkali metal hydroxide content of the solution should not be below 5% and may range up to

30%. Larger amounts of free alkali are undesirable for the reason that the solution becomes too viscous and causes emulsion difficulties when mixed with the liquid to be treated.

As an example illustrating the invention, a solution was prepared containing naphthenic acids—18.7 grams, 3,4-dihydroxydiphenyl—6.3 grams, sodium hydroxide—18.3 grams and water—56.7 grams. This solution was mixed with gasoline, prepared by high pressure thermal cracking of petroleum oil, in the ratio of 7 parts by volume of treating solution to 100 parts by volume of gasoline. The mixture was shaken for fifteen minutes in an atmosphere of nitrogen in order to exclude air. The mercaptan-sulfur in the gasoline was reduced from 0.0302% by weight to 0.0063%, thus effecting a removal of 79% of the mercaptans. The same gasoline treated with a 15% by weight sodium hydroxide solution reduced the mercaptan-sulfur to only 0.0170%, thus effecting a removal of only 44% of the mercaptans.

In the foregoing example the naphthenic acids had the following characteristics:

25

Table I

	A. P. I. gravity at 60° F-----	14.8
	Neutralization No. (mg. KOH per g.)-----	240/260
30	IBP-----	260

45 In another example, cracked gasoline containing 0.0302% by weight of mercaptan-sulfur was treated with a solution made by adding to 72.5 parts by weight of water, 15% by weight of sodium hydroxide and 12.5 parts by weight of 3,4-dihydroxydiphenyl. 7 parts by volume of this solution was shaken with the 100 parts by volume of the gasoline for fifteen minutes and the mercaptan-sulfur in the gasoline was reduced to 0.0130, thus effecting a removal of 57% of the mercaptan-sulfur as compared to a removal of only 44% of the mercaptan-sulfur by a straight 15% sodium hydroxide solution.

It will be apparent that in preparing treating reagents in accordance with the invention, the solventizers may be added to alkali metal hydroxide solutions in the form of alkali metal compounds or the alkali metal compounds may be formed in situ by the addition of the polyhydroxy-diphenyls to solutions containing appropriate amounts of alkali hydroxide. Similarly, the solutizer soaps may be formed in situ or added as such to alkali metal hydroxide solutions.

70 The specific examples given are only by way of illustration and are not intended to limit the invention to the specific quantities given or the particular compounds named. Mixtures of the various solventizers may be used as well as mixtures of different soaps. It is important, however, that sufficient quantities of free alkali,

75

solventizer and soap be present to obtain the full benefits of the invention.

Although we have found that solutions containing from 5% of free caustic alkali up to the maximum amount soluble in the solution may be used, it is preferred to use solutions which contain not over 20% of free sodium hydroxide and not over 30% of free potassium hydroxide, since it is not possible to keep in solution desirable amounts of solubility promoters when the free alkali concentrations are too high. The free alkali content will, therefore, be governed largely by the concentration of solubility promoter which is found to be the most effective and by the viscosity of the solution. Very effective results have been obtained with solutions containing from 8% of 20% of free sodium hydroxide and 10% to 30% of free potassium hydroxide. When using polyhydroxy-diphenyl as solubility promoters alone, amounts between 10% and 30% give good results and when using as a solventizer, amounts ranging from 5 to 15% by weight have been found to be sufficient. The invention also contemplates the use of alcoholic alkali as well as aqueous alkali solutions. Potassium hydroxide solutions are in general more effective in extracting mercaptans than are sodium hydroxide solutions containing equal amounts of the hydroxide.

Treating solutions in accordance with this invention can be regenerated in the same manner as caustic alkali solutions, namely, by boiling or by steam stripping, and reused either with or without adjusting the alkali concentration of the solution, and with or without further addition of solutizers and/or solventizers.

We claim:

1. The method of removing acidic bodies from otherwise neutral water immiscible organic fluids which comprises contacting said fluids with a solution containing at least 5% by weight of free alkali metal hydroxide and a substantial amount of the reaction product of alkali metal hydroxide and a polyhydroxydiphenyl.
2. Method in accordance with claim 1 in which the polyhydroxydiphenyl is a dihydroxydiphenyl.
3. Method in accordance with claim 1 in which the polyhydroxydiphenyl is a dihydroxydiphenyl in which the hydroxy groups are in ortho position to each other.
4. Method in accordance with claim 1 in which the polyhydroxydiphenyl is 3,4-hydroxydiphenyl.
5. Method of removing mercaptans from hydrocarbon liquids which comprises contacting said liquids with a solution containing at least 5% by weight of free alkali metal hydroxide and a substantial amount of the reaction product of alkali metal hydroxide and a polyhydroxydiphenyl.
6. Method in accordance with claim 5 in which the polyhydroxydiphenyl is a dihydroxydiphenyl.
7. Method in accordance with claim 5 in which the polyhydroxydiphenyl is a dihydroxydiphenyl with the hydroxy groups in ortho position to each other.
8. Method in accordance with claim 5 in which the polyhydroxydiphenyl is 3,4-dihydroxydiphenyl.
9. Method of removing mercaptans from hydrocarbon liquids which comprises contacting said liquids with a solution containing not less than 5% of free alkali metal hydroxide and not less than 5% of a polyhydroxydiphenyl in the form of its alkali metal reaction product.

10. Method in accordance with claim 9 in which the polyhydroxydiphenyl is a dihydroxydiphenyl.
11. Method in accordance with claim 9 in which the polyhydroxydiphenyl is a dihydroxydiphenyl with the hydroxy groups in ortho position to each other.
12. Method in accordance with claim 9 in which the polyhydroxydiphenyl is 3,4-dihydroxydiphenyl.
13. Method in accordance with claim 5 in which the solution in addition contains a solubility promoter selected from the group consisting of the alkali metal salts of alicyclic carboxylic acids and low boiling fatty acids and the polyhydroxydiphenyl-alkali metal hydroxide reaction product is present in sufficient amount to keep the solubility promoter in solution.
14. Method in accordance with claim 5 in which the solution in addition contains not less than 10% by weight, calculated as acid, of a solubility promoter selected from the group consisting of the alkali metal salts of alicyclic carboxylic acids and low boiling fatty acids and the polyhydroxydiphenyl-alkali metal hydroxide reaction product is present in sufficient amount to keep the solubility promoter in solution.
15. Method of removing mercaptans from hydrocarbon liquids which comprises contacting said liquids with a solution containing not less than 5% of free alkali metal hydroxide, not less than 10% by weight, calculated as acid, of a solubility promoter selected from the group of alkali metal salts of alicyclic and low boiling fatty acids, and not less than 2% by weight but sufficient polyhydroxydiphenyl in the form of its alkali metal reaction product to keep the solubility promoter in solution.
16. Method in accordance with claim 15 in which the polyhydroxydiphenyl is a dihydroxydiphenyl.
17. Method in accordance with claim 15 in which the polyhydroxydiphenyl is a dihydroxydiphenyl with the hydroxy groups in ortho position to each other.
18. Method in accordance with claim 15 in which the polyhydroxydiphenyl is 3,4-dihydroxydiphenyl.
19. The method in accordance with claim 1 in which the solution contains alkali metal naphthenates in sufficient amount to enhance the ability of the solution to remove acidic bodies from the hydrocarbon liquid and the alkali metal-polyhydroxydiphenyl reaction product is present in amounts sufficient to keep the naphthenates in solution.
20. The method in accordance with claim 5 in which the solution contains alkali metal naphthenates in sufficient amount to enhance the ability of the solution to remove acidic bodies from the hydrocarbon liquid and the alkali metal-polyhydroxydiphenyl reaction product is present in amounts sufficient to keep the naphthenates in solution.
21. The method in accordance with claim 9 in which the solution contains alkali metal naphthenates in sufficient amount to enhance the ability of the solution to remove acidic bodies from the hydrocarbon liquid and the alkali metal-polyhydroxydiphenyl reaction product is present in amounts sufficient to keep the naphthenates in solution.

LAWRENCE M. HENDERSON.
